UNITED STATES PATENT OFFICE.

HENRY B. SAUERMAN, OF CHICAGO, ILLINOIS.

MATERIAL-MOVING APPARATUS.

1,246,473.

Specification of Letters Patent. Patented Nov. 13, 1917.

Application filed May 14, 1917. Serial No. 168,463.

To all whom it may concern:

Be it known that I, HENRY B. SAUERMAN, a citizen of the United States, residing at Chicago, in the county of Cook and State of Illinois, have invented a new and useful Improvement in Material-Moving Apparatus, of which the following is a specification.

My invention relates to improvements in material-moving apparatus of the type comprising, generally stated, an inclined guide-way supporting a traveling carriage thereon with a dumping scraper-bucket connected with the carriage, and a hauling-line through the medium of which the movements of the carriage and bucket are controlled, my object being to provide a novel, simple and positively operating construction of this general type, in which the bucket is prevented from accidentally swinging to dumping position in the movement of the bucket to dumping position.

Referring to the accompanying drawings:

Fig. 1 is a view in side elevation of apparatus constructed in accordance with my invention for transferring material from one elevation to a higher elevation, the apparatus being shown in the position it assumes in moving to dumping position. Fig. 2 is a section taken at the line 2 on Fig. 1 and viewed in the direction of the arrow. Fig. 3 is a view like Fig. 1, showing the parts of the apparatus in dumping position. Fig. 4 is a view like Fig. 1 of another embodiment of my invention. Fig. 5 is a section taken at the line 5 on Fig. 4 and viewed in the direction of the arrow. Fig. 6 is a section taken at the line 6 on Fig. 4 and viewed in the direction of the arrow and Fig. 7, a view like Fig. 1 of still another embodiment of my invention.

In all of the constructions illustrated I have shown my invention as incorporated in a so-called slack-line system the inclined cable-way of which is represented at 8 and in practice would be anchored at its lower end in any suitable manner, and at its upper end supported at a higher elevation and in a manner adapting it to be slackened and made taut at will, all as is well understood in the art and therefore does not require illustration.

Referring more particularly to Figs. 1, 2 and 3, 9 is a carriage which is slidably mounted on the cableway 8 and in the form

shown comprises a pair of plates 10 and 11 connected together by bolts 12 carrying spacers 13. Located between the plates 10 and 11 are grooved pulleys 14 journaled on certain of the bolts 12 and by which the carriage engages the cable-way 8. The dumping scraper, or bucket, represented at 15 and which is supported from the carriage 9, is of a form generally employed, its forward, open, digging-end 16 being provided with an edge-portion 17 in practice usually serrated. The bucket 15 is connected at its rear end as at eyes 18 at opposite sides of the bucket with chains or cables 19 one only of which is shown, which connect at their upper ends with eyes 20 on the carriage, whereby the bucket is, in effect, pivotally hung from the carriage 9 and at such a point relative to its center of gravity that the latter will tend normally to swing to dumping position. The bucket 15 is connected at its front end with a branch 21 of the hauling-line in the form of a bridle, which unites with another branch 22 thereof at a block 23 connecting with the single section 24 of the hauling-line. The bucket is also connected, at a bail 25 thereon, with a cable 26 in the form of a bridle, which connects at its upper end as indicated at 27 with pivoted eyes 28 on a rock-member 28 located between the plates 10 and 11 and pivoted on the lower bolt 12, the rear end of the branch 22 running over a pulley 29 journaled between the plates 10 and 11, and connecting with the member 28 adjacent the connection 27. The member 28 is provided with a projection 30 which in the load-carrying position of the apparatus rests against a pin 31 extending at its ends in curved slots 32 in the plates 10 and 11 and movable up and down therein, the pin 31 passing through a yoke 33 located between the plates 10 and 11 and connected at its upper end with a cable 34 which passes over a pulley 35 on the carriage, thence over a pulley 36 on the block 23 and connects with a traveling block 37 running, at a pulley 38 thereon, on the cable-way 8, this block coöperating with a stop 39, preferably adjustable along the cable-way 8, for a purpose hereinafter described.

The parts of the apparatus are so constructed and arranged that in the normal position thereof the cable 26 will extend in the rear of the pivot of the member 28, as shown in Fig. 1, thus normally holding the

bucket in load-carrying position and the bucket cannot swing to dumping position until the member 28 has been rocked to carry the cable 26 forward of said pivot.

- 5 In the operation of the apparatus the bucket is dragged along the material to be moved, by drawing on the hauling-line and the carriage pulled along the cable-way 8 to the point of dumping. When the block 10 37 strikes the stop 39 the block 37 is arrested and continued movement of the hauling-line will operate to raise the yoke 33 and with it the pin 31 which rocks the member 28 in a clockwise direction in Fig. 1, thus carrying 15 the cable 26 in front of the pivot of the member 28, whereupon the bucket swings to dumping position and discharges, Fig. 3. Upon again drawing the hauling-line taut as, for example, after returning the bucket 20 to the point of loading by slackening the hauling-line, the connection of the branch 22 with the member 28, causes the member 28 to return to the position shown in Fig. 1 and forces the pin 31 to the position shown 25 in this figure, thus returning these parts to normal position.

It will therefore be understood from the foregoing that during the movement of the bucket along the cable-way 8 from filling 30 to dumping position, the bucket is held against dumping even should the hauling-line become slack.

The arrangement shown in Figs. 4, 5 and 35 6 is the same as that shown in the preceding figures excepting for the mechanism which rocks the member 28. In this arrangement the member 28 carries a pin 40 adapted, in the normal position of the parts, to abut against the forward edges of the carriage 40 (Fig. 4), the cable 26 connecting with collars 41 rotatable on the pin 40, and the cable 22 connecting with the member 28. The pin 40 co-operates with a latch-device 42 which is preferably formed of a forked 45 member 43, pivoted at 44 on a block 45 supported at pulleys 46 on the cable, and anchored by a cable 47 to a block 48 stationary on the cable-way 8, the purpose of this cable connection being to permit the 50 block 45 and latch 43 to give upwardly to a slight degree when struck by the pin 40 as hereafter described. The latch member 43, which is held in the position shown in Fig. 4 by a chain 49, has shoulders 50 adjacent cam-surfaces 51 which extend in the path of movement of the pin 40 when the carriage is moved to bucket-discharging position, and by engagement of the pin 40 therewith lifts the latch 43 and carries the 55 shoulders 50 over this pin, with the result that upon slackening the hauling-line, the pin 40 engages the shoulders 50 and the member 23 swings on its pivot in clockwise direction to a position in which the bucket 60 drops by gravity to dumping position. Upon 65

again drawing the hauling-line taut, as for example at the point of loading, the cable 22 returns the member 28 to normal position (Fig. 4).

In Fig. 7 I have shown my invention as 70 embodied in apparatus by which material may be transferred from a higher to a lower elevation. According to this arrangement the carriage and bucket and the connections between the carriage and bucket and between 75 the bucket and movable parts of the carriage and the hauling-line, are the same as those in the case of the construction shown in Fig. 4, excepting as to a slight change in the shape of the side plates of the carriage, and 80 the addition of a projection 52 to the member 28, like the projection 30 of Fig. 1. In the normal position of the member 28 it rests against a pin 53 which extends at its ends, carrying washers 54 beyond the plates 85 10 and 11, into registering arc-shaped slots 55 in the side plates, one only of these slots being shown, this pin extending clear through the carriage and being so disposed that it may be bodily lifted in the register- 90 ing slots 55 and in this movement, by engaging the projection 52, swinging the member 28 in clockwise direction in Fig. 7. The opposite ends of the pin 53 co-operate with levers 56 which are pivoted at 57 to extend 95 at opposite sides of the carriage and engage at their lower ends beneath the ends of the pin 53, these levers preferably being of bent form as illustrated and connected together at their left-hand ends in Fig. 7, which are 100 preferably spaced apart by a cross-bar 58. The levers 58 co-operate with a lever-tripping device 59 secured to the cable-way 8 at substantially the point at which dumping is to be effected, this device presenting an 105 inclined camming surface 60 against which the pin 58 moves and in which movement the levers 56 are rocked in an anti-clockwise direction in Fig. 7 to force the pin 53 upwardly in the slots 55 and rotate the mem- 110 ber 28. The camming surface 60 is preferably provided as the under-surface of a bar 61 pivotally connected at 62 with a block 63 secured to the cable-way 8, the free end of this lever being connected with a cable 64 115 depending from the block 63. The lever 60 should be heavy enough to cause the member 28 to be rotated in a clockwise direction in Fig. 7 against the resistance of the weight tending to prevent such rotation, the provision of the surface 60, as a part of a swing- 120 ing lever being for the purpose of providing a yielding camming surface to prevent shock.

The normal load-carrying position of the 125 parts is that illustrated in Fig. 7 wherein the bucket is positively prevented from accidentally swinging to dumping position. In the lowering of the carriage on the cable-way 8 to the point of dumping, the engage- 130

ment of the pin 58 with the lever 61 rocks the member 28 to a position in which the cable 26 extends forward of the pivot of the member 28, whereupon the bucket 15 drops by gravity to dumping position. Upon again drawing the hauling-line taut, the connection of the branch 22 with the member 28 returns the latter to normal position (Fig. 7) and likewise returns the pin 53 and levers 56 to the position shown in this figure.

It will be understood from the foregoing description of the structures illustrated that in each of them provision is made for preventing the bucket from swinging to dumping position should the hauling-line become slackened before the bucket reaches the point of dumping, and that in the operation of drawing the hauling-line taut after the dumping operation has been effected, the means which hold the bucket in load-carrying position against accidental dumping through the slackening of the hauling-line, are returned automatically to normal operating position.

While I have illustrated and described certain forms in which my invention may be embodied, I do not wish to be understood as intending to limit my invention thereto, as the same may be variously modified and altered without departing from the spirit of my invention, it being my intention to claim my invention as fully and completely as the prior state of the art will permit.

What I claim as new and desire to secure by Letters Patent, is:—

1. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move to dumping position and move said movable member in one direction on said carriage, means for releasably holding said movable member in a position in which said bucket is maintained in load-carrying position, and means for forcing said movable member out of engagement with said second-named means to permit said bucket to swing to dumping position.

2. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move

to dumping position and move said movable member in one direction on said carriage, means for releasably holding said movable member in a position in which said bucket is maintained in load-carrying position, and means operating automatically when said carriage reaches a certain position on said guide-way, to force said movable member out of engagement with said second-named means to permit said bucket to swing to dumping position.

3. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move to dumping position and move said movable member in one direction on said carriage, means for releasably holding said movable member in a position in which said bucket is maintained in load-carrying position, means for forcing said movable member out of engagement with said second-named means to permit said bucket to swing to dumping position, and means operated by drawing on the hauling-line after the bucket has been moved to dumping position, for moving said movable member into engagement with said second-named means.

4. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move to dumping position and move said movable member in one direction on said carriage, means for releasably holding said movable member in a position in which said bucket is maintained in load-carrying position, means for forcing said movable member out of engagement with said second-named means to permit said bucket to swing to dumping position, and means connected with said movable member and operated by drawing on the hauling-line after the bucket has dumped, to move said movable member into engagement with said second-named means.

5. In material-moving apparatus, the combination of a guide-way, a carriage movable along said guide-way, a dumping bucket connected with said carriage to swing thereon by gravity, when loaded, to dumping position, a hauling-line having branched sections, one of which connects with the open end of the bucket and the other of which

- operatively engages said carriage, a movable member confined on said carriage, means connecting said member with said bucket adjacent the connection of the hauling-line with the latter, said bucket, when loaded, tending to move to dumping position and move said movable member in one direction on said carriage, means for releasably holding said movable member in a position in which said bucket is maintained in load-carrying position, and means for forcing said movable member out of engagement with second-named means to permit said bucket to swing to dumping position. 5

10 6. In material-moving apparatus, the combination of a guide-way, a carriage movable along said guide-way, a dumping bucket connected with said carriage to swing thereon by gravity, when loaded, to dumping position, a hauling-line having branched sections one of which connects with the open end of said bucket, a movable member confined on said carriage and operatively connected with the other of said branched sections, means connecting said member with said bucket, said bucket, when loaded, tending to move to dumping position and move said movable member in the direction on said carriage in which it is moved by pulling the hauling-line taut, means for releasably holding said movable member in a position in which said bucket is maintained in load-carrying condition, and means for forcing said movable member out of engagement with said second-named means to permit said bucket to swing to dumping position. 15

20 7. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move to dumping position and move said movable member in one direction on said carriage, means for releasably holding said movable member in a position in which said bucket is maintained in load-carrying position, means for forcing said movable member in a direction opposite to that in which said bucket tends to move said movable member in the normal position of the parts, for moving said movable member out of engagement with said second-named means to permit said bucket to swing to dumping position. 25

30 8. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a member pivoted on said carriage, means connecting said bucket with said member eccentrically of said pivot, said bucket when loaded, tending to move to dumping position and swing said pivoted member in one direction, a stop for holding said pivoted member in a position in which said bucket is maintained in load-carrying position, and means for rotating said member in the opposite direction to a position in which the loaded bucket rotates said rotatable member in a direction opposite to that in which it tends to rotate it when in normal position, to permit said bucket to swing to dumping position. 35

40 9. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move to dumping position and move said movable member in one direction on said carriage, means for releasably holding said movable member in a position in which said bucket is maintained in load-carrying position, means for forcing said movable member in a direction opposite to that in which said bucket tends to move said movable member in the normal position of the parts, for moving said movable member out of engagement with said second-named means to permit said bucket to swing to dumping position, and means operated by drawing on the hauling-line after the bucket has been moved to dumping position, for moving said movable member into engagement with said second-named means. 45

50 10. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a member pivoted on said carriage, means connecting said bucket with said member eccentrically of said pivot, said bucket when loaded, tending to move to dumping position and swing said pivoted member in one direction, a stop for holding said pivoted member in a position in which said bucket is maintained in load-carrying position, and means for rotating said member in the opposite direction to a position in which the loaded bucket rotates said rotatable member in a direction opposite to that in which it tends to rotate it when in normal position, to permit said bucket to swing to dumping position. 55

60 11. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member

11. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a member pivoted on said carriage, means connecting said bucket with said member eccentrically of said pivot, 5 said bucket, when loaded, tending to move to dumping position and swing said pivoted member in one direction, a stop for holding said pivoted member in a position in which said bucket is maintained in load-carrying 10 position, and means operating automatically when the bucket reaches a pre-determined position on said guide-way, to rotate said member in the opposite direction to a position in which the loaded bucket rotates said 15 20 rotatable member in a direction opposite to that in which it tends to rotate it when in normal position, to permit said bucket to swing to dumping position.
12. In material-moving apparatus, the combination of a guide-way, a carriage movable along said guide-way, a dumping bucket connected with said carriage to swing thereon by gravity, when loaded, to dumping position, a hauling-line for moving the bucket 25 30 along said guide-way, a member pivoted on said carriage, means connecting said bucket with said member eccentrically of said pivot, said bucket when loaded, tending to move to dumping position and swing said pivoted 35 member in one direction, a stop for holding said pivoted member in a position in which said bucket is maintained in load-carrying position, means for rotating said member in the opposite direction to a position in which 40 the loaded bucket rotates said rotatable member in a direction opposite to that in which it tends to rotate it when in normal position, to permit said bucket to swing to dumping position, and means operated by 45 drawing on the hauling-line after the bucket has been moved to dumping position, for rotating said rotatable member to normal position for engagement with said stop.
13. In material-moving apparatus, the combination of a guide-way, a carriage movable along said guide-way, a dumping bucket connected with said carriage to swing thereon by gravity, when loaded, to dumping position, a hauling-line for moving the bucket 50 55 along said guide-way, a member pivoted on said carriage, means connecting said bucket with said member eccentrically of said pivot, said bucket, when loaded, tending to move to dumping position and swing said pivoted 60 member in one direction, a stop for holding said pivoted member in a position in which said bucket is maintained in load-carrying position, means for rotating said member in the opposite direction to a position in which 65 the loaded bucket rotates said rotatable 70 75 80 85 90 95 100 105 110 115 120 125 130
- member in a direction opposite to that in which it tends to rotate it when in normal position, to permit said bucket to swing to dumping position, said hauling-line being connected with said rotatable member, and means whereby, upon drawing said hauling-line taut, after the bucket has been moved to dumping position, said rotatable member is returned to normal position for engagement with said stop.
14. In material-moving apparatus, the combination of a guide-way, a carriage movable along said guide-way, a dumping bucket connected with said carriage to swing thereon by gravity, when loaded, to dumping position, a hauling-line having branched sections, one of said sections being connected with said bucket at the open end of the latter, a member pivoted on said carriage, means connecting said bucket with said member eccentric of the pivot of the latter, said bucket, when loaded, tending to move to dumping position and rotate said member in one direction, a stop resisting the movement of said member in said direction 90 for holding said member in a position in which said bucket is maintained in load-carrying position, and means for rotating said member in the opposite direction to a position in which the loaded bucket rotates 95 said rotatable member in a direction opposite to that in which it tends to rotate it when in normal position, to permit said bucket to swing to dumping position, the other branch of said hauling-line being connected with said member and operating upon drawing the said hauling-line taut, after the bucket has been dumped, to return said member to a position for engaging with said stop.
15. In material-moving apparatus, the combination of a guide-way, a carriage movable along said guide-way, a dumping bucket connected with said carriage to swing thereon by gravity, when loaded, to dumping position, a hauling-line for moving the bucket along said guide-way, a movable member confined on said carriage, means connecting said member with said bucket, said bucket, when loaded, tending to move 110 to dumping position and move said movable member in one direction on said carriage, means for releasably holding said movable member in a position in which said bucket is maintained in load-carrying position, and means operating automatically by continued movement of said carriage to dumping position, to force said movable member out of engagement with said second-named means to permit said bucket to swing to dumping 115 120 125 130
16. In material-moving apparatus, the combination of a guide-way, a carriage movable along said guide-way, a dumping bucket connected with said carriage to swing there-

- on by gravity, when loaded, to dumping position, a hauling-line for moving the bucket along said guide-way, a movable member confined on said carriage, means connecting said member with said bucket, said bucket, when loaded, tending to move to dumping position and move said movable member in one direction on said carriage, means for releasably holding said movable member in 5 a position in which said bucket is maintained in load-carrying position, and means operating automatically by continued forward movement of the hauling-line, to force said movable member out of engagement with said second-named means to permit said bucket to swing to dumping position.

17. In material-moving apparatus, the combination of a guide-way, a carriage movable along said guide-way, a dumping bucket connected with said carriage to swing thereon by gravity, when loaded, to dumping position, a hauling-line for moving the bucket along said guideway, a member pivoted on said carriage, means connecting said bucket with said member eccentrically of said pivot, said bucket, when loaded, tending to move to dumping position and swing said pivoted member in one direction, a stop for holding said pivoted member in a position in which said bucket is maintained in load-carrying position, and means operating by continued movement of said carriage to dumping position, to rotate said member in the opposite direction to a position in which the loaded bucket rotates said rotatable member in a direction opposite to that in which it tends to rotate it when in normal position, to permit said bucket to swing to dumping position.

18. In material - moving apparatus, the combination of a guide-way, a carriage movable along said guide-way, a dumping bucket connected with said carriage to swing thereon by gravity, when loaded, to dumping position, a hauling-line for moving the bucket along said guide-way, a member pivoted on said carriage, means connecting said bucket with said member eccentrically of said pivot, said bucket, when loaded, tending to move to dumping position and swing said pivoted member in one direction, a stop for holding said pivoted member in a position in which said bucket is maintained in load-carrying position, and means operating automatically by continued forward movement of the hauling-line, to force said movable member in the opposite direction to a position in which the loaded bucket rotates said rotatable member in a direction opposite to that in which it tends to rotate it when in normal position, to permit said bucket to swing to dumping position.

19. In material - moving apparatus, the combination of a guide-way, a carriage movable along said guide-way, a dumping bucket connected with said carriage to swing thereon by gravity, when loaded, to dumping position, a hauling-line having branched sections, one of which connects with said bucket at its open end, a member pivoted on said carriage, means connecting said bucket adjacent its open end with said member eccentric of the pivot of the latter, said bucket, when loaded, tending to move to dumping position and rotating said member in one direction on said carriage, a second

20. In material - moving apparatus, the combination of a guide-way, a carriage movable along said guide-way, a dumping bucket connected with said carriage to swing thereon by gravity, when loaded, to dumping position, a hauling-line for moving the bucket along said guide-way, a member pivoted on said carriage, means connecting said bucket with said member eccentrically of said pivot, said bucket, when loaded, tending to move to dumping position and swing said pivoted member in one direction, a stop for holding said pivoted member in a position in which said bucket is maintained in load-carrying position, and means for rotating said member in the opposite direction to a position in which the loaded bucket rotates said rotatable member in a direction opposite to that in which it tends to rotate it when in normal position, to permit said bucket to swing to dumping position.

21. In material - moving apparatus, the combination of a guide-way, a carriage movable along said guide-way, a dumping bucket connected with said carriage to swing thereon by gravity, when loaded, to dumping position, a hauling-line having branched sections, one of which connects with said bucket at its open end, a member pivoted on said carriage, means connecting said bucket adjacent its open end with said member eccentric of the pivot of the latter, said bucket, when loaded, tending to move to dumping position and rotating said member in one direction on said carriage, a second

member on said carriage operating to prevent said first-named member from swinging to a position in which said bucket dumps, said second member being movable
5 in engagement with said first-named member to a position in which the loaded bucket directs force against said first-named member in a direction for rotating it away from said second-named member, for permitting
10 the bucket to dump, a block running on said guide-way, a stop limiting the movement of said block in the movement of the apparatus to the point of dumping, and a cable connected with said block and slidingly engaging said hauling-line, the other end of 15 said cable being connected with said second member whereby the latter is actuated to operate said first-named member, the other branch of said hauling-line slidingly engaging said carriage and connected with said 20 first-named member for returning said first-named member to normal position upon drawing said hauling-line taut, after the bucket has been dumped.

HENRY B. SAUERMAN.

Copies of this patent may be obtained for five cents each, by addressing the "Commissioner of Patents, Washington, D. C."
